(57) **CLAIM**

The ornamental design for computer keyboard support, as shown and described.

DESCRIPTION

FIG. 1 is a perspective view of an embodiment of our design for a computer keyboard support;

FIG. 2 is a top plan view of the computer keyboard support of FIG. 1;

FIG. 3 is a bottom plan view of the computer keyboard support of FIG. 1;

FIG. 4 is a rear end elevation view of the computer keyboard support of FIG. 1;

FIG. 5 is a front end elevation view of the computer keyboard support of FIG. 1;

FIG. 6 is a left side elevation view of the computer keyboard support of FIG. 1;

FIG. 7 is a right side elevation view of the computer keyboard support of FIG. 1;

FIG. 8 is a perspective view of a second embodiment of our design for a computer keyboard support;

FIG. 9 is a top plan view of the computer keyboard support of FIG. 8;

FIG. 10 is a bottom plan view of the computer keyboard support of FIG. 8;

FIG. 11 is a rear end elevation view of the computer keyboard support of FIG. 8;

FIG. 12 is a front end elevation view of the computer keyboard support of FIG. 8;

FIG. 13 is a left side elevation view of the computer keyboard support of FIG. 8; and,

FIG. 14 is a right side elevation view of the computer keyboard support of FIG. 8.
